UNITED STATES PATENT OFFICE.

ALFRED G. LEGGE, OF BROCKTON, MASSACHUSETTS.

SHOE-FORM.

1,130,302.

Specification of Letters Patent.

Patented Mar. 2, 1915.

Application filed March 13, 1914. Serial No. 824,528.

To all whom it may concern:

Be it known that I, ALFRED G. LEGGE, a citizen of the United States, residing at Brockton, county of Plymouth, State of Massachusetts, have invented a certain new and useful Improvement in Shoe-Forms, of which the following is a specification, reference being had therein to the accompanying drawings.

10 My invention has for its object a new and improved adjusting device by means of which the opposing sides of a leatherboard shoe-form may be expanded after the shoe-form has been inserted in the shoe for the 15 purpose of causing the shoe-form to fit snugly into the shoe and also to adjust the shoe-form for use in shoes of different sizes. Heretofore it has been customary to employ for this purpose a simple toggle joint, composed of two members pivoted to each other 20 at the center and to the sides of the shoe-form at their ends.

Shoe-forms provided with the ordinary toggle joint can be expanded only a predetermined amount, which is limited by the throw of the toggle joint, and they must be expanded to this extent whenever in place, as otherwise the elasticity of the shoe will cause the toggle joint to resume its bent position.

30 My present invention provides a toggle joint which can be adjusted for different widths of shoes and which is less likely to be bent by the elasticity of the shoe.

35 The invention will be fully understood by reference to the following specification, taken in connection with the accompanying drawings, and the novel features thereof are pointed out and clearly defined in the 40 claims at the close of this specification.

In the drawings, Figure 1 is a bottom view of a shoe form to which my improved toggle joint is applied, the toggle joint being shown in the position occupied by it 45 when the shoe form is expanded. Fig. 2 shows the toggle joint with the members in bent position and the latch disengaged. Fig. 3 shows the toggle joint in bent position but with the latch engaging the pivot. Fig. 50 4 is a plan view of the toggle joint.

Referring now to the drawings, at A and B respectively, see Fig. 1, are shown the opposing inturned sides of the bottom of the shoe-form. The toggle joint consists of two 55 toggle members 11 and 12 pivoted at 13 and 14 to the inturned sides A and B of the shoe

form. The member 11 is preferably provided with a thumb piece 16 and the member 12 is slotted, as shown at 17, to receive a pivot stud 15 carried by the member 11 60 and which pivot-stud may be moved toward and away from the side B of the shoe form. The stud 15 serves as the central pivot of the toggle when the latter is being broken or straightened out. To the pivot stud 14, 65 coincidentally with the pivot of the toggle member 12, is secured a latch 18 having notches 19 in one edge thereof, said notches being of a size adapted to receive the said pivot stud 15. The latch is also preferably 70 provided with a thumb piece 20. In the form shown in the drawings, the latch is interposed between the two toggle members 11 and 12, and is secured to the pivot 14.

If the shoe form is to be inserted in a 75 relatively wide shoe, the toggle joint is put in the position shown in Fig. 2 and the latch 18 is swung around the pivot 14 until the end notch 19 engages the pivot stud 15. It will be seen that thereafter the pivot 80 stud 15 can not slide in the slot 17. The toggle joint in this condition is seen in Fig. 3. This construction affords a means for adjustment for different widths of shoes, the width of the shoe determining the notch 85 to be employed. As ordinarily constructed, the form will be of the width of the shoe for which it was constructed when the pivot stud is in the middle notch, and will be correctly adjusted for a shoe one size wider 90 when it is in one end notch and for a shoe one size narrower when it is in the other end notch. More notches may be provided if desired. The thumb piece 20 affords a convenient means of engaging and disengaging 95 the latch, and the latch 18 being interposed between the two toggle members 11 and 12 tends to wedge the toggle members apart and to prevent the toggle joint being displaced by pressure on the sides of the shoe 100 form.

What I claim is:

1. The combination with a shoe form provided at its bottom with opposite inturned sides, of a toggle comprising two members 105 each of which is pivoted to one of said in-turned sides, one of said members being provided with a slot and the other with a stud adjustable in said slot and serving as the central pivot of the toggle, and a latch pivoted to one of said in-turned sides coincidentally with one of said toggle members and

provided with a plurality of notches either of which may be engaged with said stud to hold the toggle in any desired position of adjustment.

5 2. The combination with a shoe form provided at its bottom with opposite inturned sides, of a toggle comprising two members each of which is pivoted to one of said in-turned sides, one of said members being provided with a slot and the other with a stud adjustable in said slot and serving as the central pivot of the toggle, and a latch pivoted to one of said inturned sides coincidently with one of said toggle members and 10 provided with a plurality of notches either of which may be engaged with said stud to hold the toggle in any desired position of adjustment, said latch being so arranged as 15 to be interposed between said toggle members when the toggle is closed.

20 3. The combination with a shoe form pro-

vided at its bottom with opposite inturned sides, of a toggle comprising two members each of which is pivoted to one of said in-turned sides, one of said members being provided with a slot and the other with a stud adjustable in said slot and serving as the central pivot of the toggle, and a latch pivoted to one of said inturned sides coincidently with one of said toggle members and 25 provided with a plurality of notches either of which may be engaged with said stud to hold the toggle in any desired position of adjustment, said latch and one of said toggle members being each provided with an 30 operating thumb-piece.

In testimony whereof I affix my signature, in presence of two witnesses.

ALFRED G. LEGGE.
